(57) CLAIM

The ornamental design for the foldable mat with pillow, as shown.

DESCRIPTION

FIG. 1 is a perspective view of the foldable mat with pillow in accordance with our new design.

FIG. 2 is a left-side elevational view of the foldable mat with pillow of FIG. 1.

FIG. 3 is a right-side elevational view of the foldable mat with pillow.

FIG. 4 is a top plan view of the foldable mat with pillow.

FIG. 5 is a bottom plan view of the foldable mat with pillow.

FIG. 6 is a front elevational view of the foldable mat with pillow; and,

FIG. 7 is a rear elevational view of the foldable mat with pillow.

The evenly dashed broken lines shown on claimed surfaces depict portions of the foldable mat with pillow that form no part of the claimed design.

1 Claim, 4 Drawing Sheets
